GUSTAVUS E. STRAUSS, OF NEW YORK, N. Y.

LOOSE-LEAF FILE.

1,333,350.

Specification of Letters Patent.

Patented Mar. 9, 1920.

Application filed January 17, 1919. Serial No. 271,691.

To all whom it may concern:

Be it known that I, GUSTAVUS E. STRAUSS, a citizen of the United States, and a resident of the city of New York, in the county of New York and State of New York, have invented certain new and useful Improvements in Loose-Leaf Files, of which the following is a specification.

The present invention relates to improvements in devices for filing or temporarily binding loose sheets, such as, for instance, letters, bills, etc.

The main object of the invention is to provide a simple device of the character mentioned, which is capable of extension, to increase the capacity of the file.

Another object of the invention is to produce a file that can be placed vertically into a cabinet and handled therein conveniently.

A further object of the invention is to generally improve and simplify files of the type specified, and to devise one which is capable of manufacture on a commercial scale, or, in other words, one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:

Figure 1 is a sectional perspective view of a file cabinet and a number of files, constructed in accordance with the present invention, positioned therein; Fig. 2 is a front elevation of the improved file; Fig. 3 is a side elevation thereof; Fig. 4 is a bottom plan view of the same; Fig. 5 is a top plan view of the same; Fig. 6 is a front elevation of a portion of the file, on a larger scale; Fig. 7 is a section taken on line 7-7 of Fig. 6; Fig. 8 is a section taken on line 8-8 of Fig. 6; Figs. 9 to 12, inclusive, are

sections similar to the one shown in Fig. 8 with the elements in other positions; and Fig. 13 is a perspective view, showing the manner of mounting the clamping plate of the file on one of the extensible elements thereof.

In the drawings, the numeral 20 indicates the base or back plate of the improved file, made of any suitable material, such as for instance, metal. This plate is provided with sides 21 and a head 22, connecting the said sides. These sides and head extend, preferably, at right angles to the body of the plate 20. When of metal, the sides and head are made, preferably, integral with the plate, as clearly appears from the drawings, but, when made of wood, they are, preferably, made of separate pieces and attached to the plate in any suitable manner. The head 22 and the portions of the sides 21 adjacent thereto are provided with inwardly extending flanges 22' and 21', respectively, said flanges being disposed in a plane parallel to that of the plate 20. The base plate, with its sides and head, constitutes a shallow tray, that is open at its end 23, to permit the loose leaves therein to be easily handled.

A plurality of extension members, in the present case two, denoted by the numerals 24 and 25, are mounted, in a manner presently to be described, within the tray, each of said extension members being formed, preferably, of a metal strip. Each extension member comprises a body portion 26, that is disposed parallel to the head 22 of the plate 20, and provided at its ends with short legs 27, that are bent at right angles to the body portion 26 and extend in parallel relation to the sides 21, above mentioned. The extension member 24 is embraced, as it were, by the sides and head of the plate 20, and the extension member 25 by the extension member 24. The extension member 24 is substantially Z-shaped cross-section, its outwardly bent flange 28 being in alinement with and coöperating, in a manner herein-after to be described, with the flange 22' of the head 22, and its inwardly bent flange 29 coöperating with the outwardly bent flange 30 of the extension member 25, the latter being substantially L-shaped. The flanges 28, 29 and 30 of the two extension members extend, preferably, all around the same, and serve, in coöperation with the flange 22' above referred to, to prevent a dis-

engagement of the extension members from the shallow tray and also from each other. The extension members are, of course, disposed as close as possible to the head 22 of the plate 20, and the distance between the short legs of the extension member 25 is such as to accommodate the largest loose leaf to be filed.

Adjacent the flange 28, there is formed in each short leg 27 of the extension member 24 an aperture 31, said two apertures being in alinement. A second aperture 32 is formed in each short leg of the extension member 24, in proximity of its flange 29, and these apertures 32 are also in alining positions. In a similar manner are formed in each short leg 27 of the extension member 25 two apertures, indicated at 33 and 34, the apertures 33 and in the two legs being in alinement, and so also the apertures 34 therein. In each side 21 of the base plate 20 is formed an opening 35, the two openings being in alining positions. Through each of these openings extends a headed stud 36, which is slidably disposed in a tubular projection 37 on the outer face of the respective side 21. Each stud is under the action of a spring 38, one end of said spring bearing against a cap 39, closing the projection, and the other end being attached in any suitable manner to the stud. The heads 40 of the studs are larger in diameter than the projections 37, and bear against the caps on the said projections. From this it appears that the head 40 of each stud is spaced from the adjacent outer face of the respective side 21. The purpose of this arrangement will appear hereinafter. The studs are each of a length so as to be projected through the apertures in the adjacent two short legs of the extension members, to hold the latter in the desired position in relation to each other and to the base plate 20.

To the free edge of the body portion 26 of the extension member 25 is attached a clamping body 41. This body may be of any suitable construction, the one herein described being shown only for purposes of illustration. It comprises a yoke-shaped wire piece, the ends of which are coiled around a spindle 42, that is carried by the extension member 25, the free ends 43 of the coils bearing against the said extension member. The clamping member is made of spring wire, the spring coils having a tendency to force the free end 41' of the clamping body toward the plate 20 of the file.

To the outer face of the head 22 of the plate 20 is attached, in any suitable manner, an index holder 44 of any suitable construction, which is adapted to detachably hold an index plate 45, the latter being made of any suitable material and is insertable into and removable from the said

holder. On the index plate may be provided an identification mark 45', indicating the contents of the file.

The operation of this device is as follows: When the file is first being assembled, the studs 36 are seated in the apertures 32 and 34 in the extension members 24 and 25, respectively. Both extension members are thus held within the tray-shaped file, their heights corresponding substantially to those of the sides 21 and head 22 on the plate 20 (Figs. 2 to 8, inclusive). To insert a leaf into the file, the clamping body 41 thereof is swung around the spindle 42 against the action of its spring coils, after which the leaf is placed within the tray and the clamping body released, whereby the latter presses against the leaf, holding it within the tray.

If it is intended to increase the capacity of the file, the studs 36 are disengaged from the apertures 34 in the extension member 25, and the latter shifted until its apertures 33 are in registering positions with the said studs, after which the said studs are seated in the last-named apertures (Fig. 9). If a further extension is necessary, the studs 36 are disengaged from the extension member 25, in which case the coöperating flanges 29 and 30 of the extension members 24 and 25, respectively, limit the extent of the outward movement of the extension member 25 (Fig. 10). Still further extension may be obtained by disengaging the studs 36 from the apertures 32 in the extension member 24 and seating the same in the apertures 31 therein (Fig. 11). The largest extension is obtained when the studs 36 are disengaged from the extension member 24, and the flange 28 on the last-named extension member is permitted to engage with the flange 21' on the sides 21 of the plate 20 (Fig. 12).

By these operations, the heights of the sides 21 and head 22 of the plate 20 are increased, so that the file is adapted to hold a greater number of leaves.

It is obvious that, while herein two extension members have been shown, any other suitable number may be employed. Furthermore, attention is called to the fact that, while herein a specific means has been disclosed for positioning the extension members in relation to the sides and head of the plate 20 of the file, any other construction may be made use of without departing from the invention, which lies mainly in the provision of means for increasing, at will, the height of said sides and head, in combination with a clamping member carried by one of the extension members. It should be noted also that, while herein in each short leg of the extension members two apertures have been shown, any other suitable number may be provided therein.

The files may be placed vertically into a cabinet, denoted by the numeral 46 in Fig. 130

1 of the drawings. To this cabinet are attached, adjacent and parallel to two of its sides 47, rods 48, which are disposed in proximity of the top of the file cabinet. 5 These rods are spaced apart so that the files may be suspended therefrom with their projections 37 resting upon the said rods. The files are prevented from being shifted laterally on these rods, but are shiftable in the 10 direction of the longitudinal axes of these rods.

What I claim is:—

1. In a file for holding loose leaves, the combination with a back plate having sides 15 and a head disposed substantially at right angles to the body thereof, and means mounted thereon for increasing the height of said sides and head so as to increase the capacity of the file. 20 2. In a file for holding loose leaves, the combination with a back plate having sides and a head disposed substantially at right angles to the body thereof, of an extension member thereon comprising a body portion 25 and legs, said body portion being disposed in proximity of and in parallel relation to said head and said legs being arranged in proximity of and in parallel relation to said sides, and means for adjusting the position 30 of said extension member in relation to said head and sides to increase the height of said head and sides, at will.

3. In a file for holding loose leaves, the combination with a back plate having sides 35 and a head disposed substantially at right angles to the body thereof, means mounted thereon for increasing the height of said sides and head so as to increase the capacity of the file, and a clamping body carried by 40 said last-mentioned means.

4. In a file for holding loose leaves, the combination with a back plate having sides and a head disposed substantially at right angles to the body thereof, means mounted 45 thereon for increasing the height of said sides and head so as to increase the capacity of the file, and a spring-pressed clamping body hinged to said last-mentioned means.

5. In a file for holding loose leaves, the combination with a back plate having sides and a head disposed substantially at right angles to the body thereof, of an extension member thereon comprising a body portion 55 and legs, said body portion being disposed in proximity of and in parallel relation to said head and said legs being arranged in proximity of and in parallel relation to said sides, means for adjusting the position of said extension member in relation to said head and sides to increase the height of said head and sides, at will, and a clamping body carried by said extension member.

6. In a file for holding loose leaves, the combination with a back plate having sides 65 and a head disposed substantially at right

angles to the body thereof, of an extension member thereon comprising a body portion and legs, said body portion being disposed in proximity of and in parallel relation to said head and said legs being arranged in 70 proximity of and in parallel relation to said sides, means for adjusting the position of said extension member in relation to said head and sides to increase the height of said head and sides, at will, and a spring-pressed 75 clamping body hinged to said extension member.

7. In a file for holding loose leaves, the combination with a back plate having sides and a head disposed substantially at right 80 angles to the body thereof, said sides being provided with two registering apertures, of an extension member on said back plate comprising a body portion and legs, said body portion being disposed in proximity of and in parallel relation to said head and 85 said legs being arranged in proximity of and in parallel relation to said sides, said legs being each provided with a row of apertures in a line substantially at right 90 angles to said back plate and each aperture being adapted to register with the aperture in the adjacent side, and a stud extending through the registering apertures of each side and leg. 95

8. In a file for holding loose leaves, the combination with a back plate having sides and a head disposed substantially at right angles to the body thereof, said sides being provided with two aligned apertures, of an 100 extension member on said back plate comprising a body portion and legs, said body portion being disposed in proximity of and in parallel relation to said head and said legs being arranged in proximity of and in parallel relation to said sides, said legs being each provided with a row of apertures in a line substantially at right angles to said back plate and each aperture being adapted to register with the aperture in 110 the adjacent side, a stud extending through the registering apertures of each side and leg, and a clamping body carried by said extension member.

9. In a file for holding loose leaves, the combination with a back plate having sides and a head disposed substantially at right angles to the body thereof, said sides being provided with two aligned apertures, of an 115 extension member on said back plate comprising a body portion and legs, said body portion being disposed in proximity of and in parallel relation to said head and said legs being arranged in proximity of and in parallel relation to said sides, said legs being each provided with a row of apertures in a line substantially at right angles to said back plate and each aperture being adapted to register with the aperture in the adjacent side, a stud extending through the 125 130

registering apertures of each side and leg, and a spring-pressed clamping body hinged to said extension member.

10. In a file for holding loose leaves, the combination with a back plate having sides and a head disposed substantially at right angles to the body thereof, said sides being provided with two aligned apertures, of an extension member on said back plate comprising a body portion and legs, said body portion being disposed in proximity of and in parallel relation to said head and said legs being arranged in proximity of and in parallel relation to said sides, said legs being each provided with a row of apertures in a line substantially at right angles to said back plate and each aperture being adapted to register with the aperture in the adjacent side, and a stud extending through the registering apertures of each side and leg, said studs being provided adjacent to the outer faces of said sides each with a head spaced from said outer faces.

11. In a file for holding loose leaves, the combination with a back plate having sides and a head disposed substantially at right angles to the body thereof, of a plurality of extension members thereon comprising each a body portion and legs, the body portions of said extension members being disposed in proximity of and in parallel relation to said head and the legs of said extension members being arranged in proximity of and in parallel relation to said sides, connecting means between one of said extension members and said sides to increase the height of the latter, at will, and connecting means between said back plate members and extension members for adjusting the relative positions thereof to increase, at will, the combined height of the extension members connected to said sides.

12. In a file for holding loose leaves, the combination with a back plate having sides and a head disposed substantially at right angles to the body thereof, of a plurality of extension members thereon comprising each a body portion and legs, the body portions of said extension members being disposed in proximity of and in parallel relation to

said head and the legs of said extension members being arranged in proximity of and in parallel relation to said sides, connecting means between one of said extension members and said sides to increase the height of the latter, at will, connecting means between said back plate members and extension members for adjusting the relative positions thereof to increase, at will, the combined height of the extension members connected to said sides, and a clamping body carried by one of said extension members.

13. In a file for holding loose leaves, the combination with a back plate having sides and a head disposed substantially at right angles to the body thereof, of a plurality of extension members thereon comprising each a body portion and legs, the body portions of said extension members being disposed in proximity of and in parallel relation to said head and the legs of said extension members being arranged in proximity of and in parallel relation to said sides, connecting means between one of said extension members and said sides to increase the height of the latter, at will, connecting means between said back plate members and extension members for adjusting the relative positions thereof to increase, at will, the combined height of the extension members connected to said sides, and a spring-pressed clamping body hinged to one of said extension members.

14. In a file for holding loose leaves, the combination with a back plate having sides and a head disposed substantially at right angles to the body thereof, and sidewardly projecting studs mounted upon said sides.

15. In a file for holding loose leaves, the combination with a back plate having sides and a head disposed substantially at right angles to the body thereof, and sidewardly projecting headed studs mounted upon said sides, the heads of said studs being spaced from the outer surfaces of said sides.

Signed at New York, in the county of New York and State of New York, this 7th day of January, A. D., 1919.

GUSTAVUS E. STRAUSS
